UNITED STATES PATENT OFFICE.

ROBERT M. DIXON, OF EAST ORANGE, NEW JERSEY, ASSIGNOR TO THE SAFETY CAR HEATING & LIGHTING COMPANY, A CORPORATION OF NEW JERSEY.

HEATER FOR REFRIGERATOR-CARS.

968,331.

Specification of Letters Patent. Patented Aug. 23, 1910.

Application filed May 19, 1908. Serial No. 317,719.

To all whom it may concern:

Be it known that I, ROBERT M. DIXON, residing at East Orange, in the county of Essex and State of New Jersey, have invented 5 certain new and useful Improvements in Heaters for Refrigerator-Cars, of which the following is a full, clear, and exact description, such as will enable others skilled in the art to which it appertains to make and 10 use the same.

My invention relates to heating systems, and more especially to hot water heating systems designed to be used in connection with railway cars. One object thereof is to 15 provide an improved hot water heating system particularly adapted for employment in certain types of freight cars. Another object thereof is to provide a heating system of the above type wherein the chances of 20 accidental fires are reduced to a minimum.

Other objects will be in part obvious and in part pointed out hereinafter.

The invention accordingly consists in the features of construction, combinations of 25 elements and arrangement of parts which will be exemplified in the embodiment hereinafter set forth, and the scope of the application of which will be indicated in the following claims.

30 In the accompanying drawings, wherein is illustrated one of the various possible embodiments of my invention, Figure 1 is a top plan view showing diagrammatically the outline of the floor of a freight car provided with my invention, Fig. 2 is a view in elevation of a portion of the heating system, with the heater secured underneath the sills of a car, Fig. 3 is a view taken transversely 35 through the body portion of a freight car 40 wherein certain portions of this embodiment of my invention are positioned, some of the parts being shown in elevation, and Fig. 4 is a sectional view taken on line 5-5 of Fig. 3.

45 Similar reference characters refer to similar parts throughout the several views of the drawings.

In order that the more important objects 50 of my invention may be more clearly comprehended, it may here be noted that in some types of freight cars, as refrigerator cars, it is desirable to provide heating apparatus of some character whereby a slight degree of heat may be afforded so as to insure 55 against the perishable freight carried by

such cars becoming damaged by frost. As such cars are not open for inspection and must necessarily for long intervals of time be without care or attention, the employment of fuel burning heaters in this relation 60 has hitherto proven objectionable on account of the likelihood of their setting the structures afire. I have therefore found it desirable, in obviating the above and other objections to the use of stoves in this relation, to provide a structure wherein all danger 65 of cars catching on fire is eliminated, and it will be apparent from the more detailed description of my invention into which I shall presently enter, that I have 70 secured these ends through the provision of an efficient heating apparatus.

Referring now to the drawings, I have shown the preferred adaptation of my invention applied to a refrigerator car, indicated at 1, the roof 2 of which has, in Fig. 1, been removed to better illustrate the arrangement of the circulating system. Underneath the sill 3 at one side of the car is secured a casing 4, within which is located 75 a heater 5. The heater is arranged to be fed from the top and has its fire box surrounded by a water retainer or jacket 6, from which a water feed pipe 7 extends at its upper portion and which has leading 80 thereinto at its lower portion the return pipe 8 of the heating system. The products of combustion from the heater are discharged therefrom into the atmosphere by means of a flue or stack 9 which extends 85 therefrom upwardly through the body of the car at one side thereof and at its top, above the roof of the car.

Encircling stack 9, and providing a space therebetween, is a water-jacket 10, as clearly 90 shown in Figs. 3 and 4 of the drawings. This water-jacket extends the entire length of stack 9 within the body of the car, and is closed against leakage about stack 9 at its lower portion by a fitting 11, into which 95 leads the water feed conduit extending from heater 5. The upper end of water-jacket 10 is also closed tightly against stack 9 by means of fitting 12 and gland 13. Water-jacket 10, intermediate its length, is provided with a fitting 14 from which leads 100 the circulating conduit 15 of the hot water heating system, which, as shown in the drawings, extends lengthwise of the same a short 105 distance below the roof, the extreme end of 110

said system of piping being connected to heater 5 by means of return-pipe 8.

Threaded into an opening 16 in water-jacket 10 above the highest point in the circulating system is a funnel 17 by means of which the entire system may be filled with water, said funnel being closed by means of a valve 18. It will be noted that water-drum 10 extends above the highest point in the 10 circulating system and thus provides an expansion tank therefor, and, in order to provide against the accumulation of an excess of pressure in the system, fitting 12 at the upper end of water-jacket 10 has threaded therein a short pipe 19 which carries a suitable pop or safety valve 20.

The operation of my invention should be obvious without further description, but it will be noted that the hot water flowing 20 from the heater will circulate through feed pipe 7, water-jacket 10 which surrounds the stack of said heater, thence through the circulating system arranged about the car, said circulating water returning to the heater 25 through return-pipe 8. It will thus be seen that stack 9 is insulated from the structure of the car, and all likelihood of said structure becoming ignited from contact with said stack thereby prevented. Moreover, the 30 heated products of combustion passing through said stack are utilized in heating the circulating water.

It will accordingly be apparent that I have provided a construction characterized 35 by simplicity and efficiency, and one wherein is realized all the aims and objects of my invention above specified, and others not mentioned herein, as I deem my invention susceptible of being employed with great 40 facility in a variety of other relations, although it is especially well adapted in the relation shown.

As many changes could be made in the above construction and many apparently 45 widely different embodiments of my invention could be made without departing from the scope thereof, I intend that all matter contained in the above description or shown in the accompanying drawings shall be interpreted as illustrative and not in a limiting sense. I desire it also to be understood that the language used in the following 50 claims is intended to cover all of the generic and specific features of the invention herein

described and all statements of the scope 55 of the invention, which, as a matter of language, might be said to fall therebetween.

Having described my invention, what I claim as new and desire to secure by Letters Patent is:—

1. A refrigerator car heating system comprising, in combination, a heater supported underneath the body of a car, an inclosing casing about said heater, a stack extending from said heater through the body of the car, through the roof thereof to the atmosphere, a water-jacket positioned about said stack providing a space therebetween for the circulation of water, said water-jacket being closed about said stack at its 70 upper and lower ends by means of suitable fittings, a water-feed conduit extended between the upper portion of said heater and the fitting upon the lower end of said water-jacket, a water-circulating system leading from said water-jacket intermediate its ends and extending about the interior of the car underneath the roof thereof, a connection between said circulating system and said heater whence the circulating water is returned to the heater, means connected with said water-jacket above the level of the circulating water in said system whereby the system may be filled, the upper portion of 80 said water jacket providing an expansion 85 tank for the system, and means connected with said water-jacket for relieving the system of excess pressure.

2. In a refrigerator car, in combination, a heating system therefor comprising a 90 source of heat located without the car, a stack leading therefrom passing through the interior of the car, a water jacket positioned about said stack within the car so as to insulate to some extent said stack from the 95 immediate locality, and a circulating system located within said car and in communication with said jacket for transferring the heat thereof to localities remote therefrom resulting in the more equal distribution of 100 the heat.

In testimony whereof I affix my signature, in the presence of two witnesses.

ROBERT M. DIXON.
